(57) **CLAIM**

We claim the ornamental design for a GPS receiver, as
shown and described.

DESCRIPTION

FIG. 1 is an upper right front perspective view of a GPS
receiver;

FIG. 2 is a lower left front perspective view thereof;

FIG. 3 is a front elevational view thereof;

FIG. 4 is a right side elevational view thereof;

FIG. 5 is a rear elevational view thereof;

FIG. 6 is a left side elevational view thereof;

FIG. 7 is a top plan view thereof; and,

FIG. 8 is a bottom plan view thereof.
